Patented Oct. 21, 1890.

UNITED STATES PATENT OFFICE.

CHARLES BOOZE, OF BUFFALO, NEW YORK, ASSIGNOR TO M. H. BIRGE
& SONS, OF SAME PLACE.

DESIGN FOR WALL-PAPER.

SPECIFICATION forming part of Design No. 20,222, dated October 21, 1890.

Application filed September 27, 1890. Serial No. 366,375. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of a continuous branch of roses and leaves arranged in a horizontal wavy line and running under and over a continuous scroll ornament arranged, also, in a horizontal wavy line 15 running in an opposite direction from the wavy line of roses and leaves, as represented in the accompanying photograph. A circular ornament is arranged at every alternate point of intersection of the ornamental scroll

with the branch of roses and leaves, and at 20 the point of intersection of the scroll and branch of roses and leaves between the circular ornaments is arranged a rose in full bloom. Light parallel lines are arranged horizontally above and below the ornamental scroll and 25 wavy line of roses and leaves and form the edges of the border.

My design is more particularly intended and designed for ceiling decoration.

What I claim is—
The design for wall-paper herein shown and described.

Witness my hand this 13th day of September, 1890.

CHARLES BOOZE.
